CLAMP ACTUATING MECHANISM FOR
STAVE JOINTERS

Willard R. Butterworth, Jr., Memphis, Tenn.

Application December 16, 1947, Serial No. 792,008

3 Claims. (Cl. 147—29)

1
This invention relates to clamp actuating mechanisms for stave jointers of the general type shown in the patent to W. V. Grace, No. 1,716,520, issued June 11, 1929.

Stave jointers of this type are used for jointing or dressing up the edges of barrel staves, which, when placed in the machine for jointing, are solidly clamped for the jointing operation. This movement is usually accomplished by foot power, the heavy pressure necessary for clamping making it necessary that the clamping movement be largely multiplied. In the application of the clamping pressure, as recited in the above mentioned patent, inequality in thickness of the ends of the stave makes it necessary to equalize the pressure applying force in order that both ends of the stave will be equally clamped.

The objects of the present invention are, in a stave jointing machine;

To provide means to equalize the pressure applying force on the two clamps;

To provide linkage connecting the clamp operating mechanism and the clamps, which will equalize the pressure of the operating mechanism on the clamps without lateral binding;

To provide power actuated operating mechanism and means for controlling the operation thereof; and

To provide stave clamping mechanism, and power actuated operating mechanism, and means for linking said mechanisms to successively effect stave clamping action and stave jointing movements.

The means by which the foregoing and other objects are accomplished, and the manner of their accomplishment, will readily be understood from the following specification on reference to the accompanying drawings, in which:

Fig. 1 is a side elevation of a stave jointer in accordance with the above mentioned patent showing my improved equalizing means applied to the clamping mechanism thereof.

Fig. 2 is an enlarged sectional elevation of the clamping mechanism taken on the line II—II of Fig. 1.

Fig. 3 is a similarly enlarged sectional elevation on the line III—III of Fig. 4 showing a modified actuating mechanism.

Fig. 4 is a similarly enlarged fragmentary side elevation showing the stave carrier and the modified form of actuating mechanism.

Referring now to the drawings in which the various parts are indicated by numerals, 12 is a circular disc or head of the usual dished type carrying knives 14. The disc is mounted on a 55

shaft 16, which is suitably journaled in side frames 17 and is driven to rotate the disc and cause the knives 14 to plane or joint an edge of the stave blank and properly bevel this edge so that the stave, when assembled in the barrel, will tightly abut the similarly formed edge of an adjoining stave. Adjacent the face of the disc 12 is a stave carrier including a table 18 on which a stave 20 is supported for such cutting action. The table includes laterally disposed seats 22 against which the ends of the stave are clamped. The table 18 is supported by legs 24 which integrally extend from a rocker bar 26 having bearings 26A journaled in boxes 28 supported by members 30 of the frame 17, the table 18 being oscillatable about the bearings 26A to move the stave 20 carried by the table against the cutting knives 14. The seats 22 are slotted to receive clamping arms 32 which are pivotally mounted on pins 34. The arms 32 extend above the table and have inwardly and downwardly curved arch portions 32A which carry gripping members 36 adapted for clamping the ends of the staves against the seats 22. Below the table the arms 32 have inwardly extending portions 32B which are connected by pivotally attached, vertically disposed links 38, to a horizontally disposed equalizer bar 40. The bar 40 is pivoted at its center to a head 42 on the upper end of a coupling rod 44, which rod is slidably mounted through the rocker bar 26 and an integral guide 26B thereabove.

Power is applied to the arms by a pneumatic cylinder piston assembly 45, 46, having a projecting piston rod 47. Compressed air is supplied to the cylinder from a suitable source through a pipe 48 and conventional four-way valve 50 manually actutable by a foot pedal 52 to optionally establish flow through a pipe 54 into the lower end of the cylinder, or through a pipe 55 into its upper end, both pipes being flexible to allow cylinder oscillation.

In the forms shown in Figs. 3 and 4, the coupling rod 44 projects downward and has a head 56 on its lower end which is coupled by a pin 57 through a link 58 and a pin 60 to a rocker arm 62 which is mounted on and keyed to a rocker shaft 64. The shaft 64 is suitably journaled and supported by brackets 66. Laterally offset from the arm 62 is a second arm 68 which is also carried by and keyed to the rocker shaft 64. The outer end of the arm 68 lies below the cylinder 45 and is connected by a pin 70 to the piston rod of the cylinder 47.

In the form of the device shown in Figs. 1 and 2

the second arm 68 is dispensed with and the cylinder 45 is positioned directly in line with the arm 62. The arm 62 is extended beyond the pin 60 and the piston rod 47 is coupled by a pin 60A to the arm 62.

In both forms of the device it will be noted that the pin 60, through which the link 58 is connected to the arm 62, is positioned forwardly of the line of the coupling rod 44 extended, so that the link 58 is angularly disposed with respect to the coupling rod, and on exertion of a downward pull by the arm 62 on the pin 60, tends to swing the lower end of the coupling rod forward and the upper portion of the table 18 backward toward the cutting disc 12.

In use the foot pedal 52 is released or rocked to actuate the valve 50, allow air to flow through pipe 54 into the lower end of the cylinder and release air pressure through pipe 55 from the upper end of the cylinder, raising the piston rod 47. The rod 47 either directly as in Figs. 1 and 2, or through the arm 68 as in Figs. 3 and 4, raises the arm 62 and through the link 58 raises the coupling rod 44 and the equalizer bar 40. The bar 40 through the links 38, raises the clamping bars 32B and gripping members 36 carried thereby. The stave 20 is placed on the table and the pedal 52 rocked to admit air through the pipe 55 into the upper end of the cylinder 45, and through pipe 54 release pressure on the lower end, forcing the piston and piston rod 47 downward and depressing the arm 62, either directly by action on the pin 60A (Fig. 2) or through movement of the arm 68 (Fig. 3).

At the beginning of the downward movement the head 57 on the lower end of the coupling rod 44 is against the lower side of the rocker bar 26 and extremely close to the axis of that bar, and downward movement of the piston and piston rod 47 exerts a clamping pull on the arms 32 until the gripping members 36 clamp the end of the stave 20 against the seats 22 and stop downward movement of the coupling rod 44. At this time the head 57 has moved away from the rocker bar 26 and further downward pull tends to straighten out the angularity of the link 58 and the coupling rod 44 and swing the head 57 forward (to the left in Figs. 2 and 3) and the stave 20 to the right in those views into cutting contact with the knives 14, this action continuing until such material as is desired has been removed by the knives from the stave, the limit of this cutting movement being shown in these figures. Subsequent rocking, or if desired, release of the foot pedal 52, cuts off air flow through the pipe 55 and establishes opposite flow through the pipe 54, raising the piston 46 and swinging the stave away from the knives and releasing the gripping members 36, allowing the stave to be reversed for work on the opposite edge or to be removed and another stave to be substituted.

I claim:

1. In a stave jointing machine which includes a frame and a cutter disc journalled thereby; a stave carrier including a rocker bar journalled in bearings carried by said frame forwardly of and below said disc, a table including seat portions, spaced above and carried by said bar, clamping members pivotally attached to said table for securing the end portions of a stave against said seat portions, an equalizer bar below said table, linkage inter-connecting said clamp members and said bar; and a coupling rod pivotally engaged at its upper end to said bar and depending therefrom through and slidably guided by said rocker

bar; a cylinder forward of said rocker bar pivotally attached at its upper end to, and depending from, said frame, brackets carried by said frame rearward of said rocker bar, a shaft carried by said brackets below said cylinder, arm means carried by said shaft and projecting forwardly beyond said rocker bar into underlying relation to said cylinder, a piston reciprocably mounted in said cylinder, a piston rod projecting therefrom and pivotally connected to said arm means, and a link pivotally connected at its lower end to said arm means forward of said rocker bar and extending upwardly and rearwardly to said coupling rod and being pin connected thereto, a source of air under pressure and manually controlled means for establishing flow of air to either end of said cylinder and concurrent release of air from the respectively opposite end thereof.

2. In a stave jointing machine which includes a frame and a cutter disc journalled thereby; a stave carrier including a rocker bar journalled in bearings carried by said frame forwardly of and below said disc, a table including seat portions, spaced above and carried by said bar, clamping members pivotally attached to said table for securing the end portions of a stave against said seat portions, an equalizer bar below said table, linkage inter-connecting said clamp members and said bar; and a coupling rod pivotally engaged at its upper end to said bar and depending therefrom through and slidably guided by said rocker bar; a cylinder forward of said rocker bar pivotally attached at its upper end to, and depending from, said frame, brackets carried by said frame rearward of said rocker bar, a shaft journalled in said brackets, arms secured on said shaft and projecting forwardly beyond said rocker bar, a first of said arms extending into underlying relation to said cylinder, a piston reciprocably mounted in said cylinder, a piston rod projecting therefrom and pivotally connected to said first arm, and a link pivotally connected at its lower end to the other of said arms forward of said rocker bar and extending upwardly and rearwardly to said coupling rod and being pin connected thereto; a

3. In a stave jointing machine which includes a frame and a cutter disc journalled thereby; a stave carrier including a rocker bar journalled in bearings carried by said frame forwardly of and below said disc, a table including seat portions, spaced above and carried by said bar, clamping members pivotally attached to said table for securing the end portions of a stave against said seat portions, an equalizer bar below said table, linkage inter-connecting said clamp members and said bar; and a coupling rod pivotally engaged at its upper end to said bar and depending therefrom through and slidably guided by said rocker bar; a cylinder forward of said rocker bar pivotally attached at its upper end to and depending from said frame, brackets carried by said frame rearward of said rocker bar, a shaft journalled in said brackets, arms secured on said shaft and projecting forwardly beyond said rocker bar, a first of said arms extending into underlying relation to said cylinder, a piston reciprocably mounted in said cylinder, a piston rod projecting therefrom and pivotally connected to said first arm, and a link pivotally connected at its lower end to the other of said arms forward of said rocker bar and extending upwardly and rearwardly to said coupling rod and being pin connected thereto; a

2,475,475

5

source of air under pressure and manually controlled means for establishing air flow to either end of said cylinder and concurrent release from the respectively opposite end thereof.
